GRINDING MACHINE

Walter G. Wessman, Fairfield, Conn.

Application June 21, 1944, Serial No. 541,381

28 Claims. (Cl. 51—50)

1

This invention relates to new and useful improvements in abrading apparatus and has particular relation to a machine adapted for very rapid grinding, lapping and polishing operations.

An object of the invention is to provide a machine adapted for rapid and accurate grinding, lapping and polishing of work and which machine while especially adapted for the grinding, lapping and polishing of cemented tungsten carbide may be used for the grinding, lapping and polishing of tool steel and the like as well as of relatively soft metals and alloys, such as alloys containing copper, lead, tin and graphite, as well as non-metallics.

Other objects and advantages of the invention will become apparent from a consideration of the following detailed description taken in connection with the accompanying drawings wherein satisfactory embodiments of the invention are shown. However, it is to be understood that the invention is not limited to the details disclosed but includes all such variations and modifications as fall within the spirit of the invention and the scope of the appended claims.

In the drawings:

Fig. 1 is a front elevational view of a form of the machine adapted for multi-angle grinding:

Fig. 2 is a top plan view of said machine:

Fig. 3 is an end elevational view taken as looking from the right in Fig. 1;

Fig. 4 is a sectional view taken as along the line 4—4 of Fig. 6;

Fig. 5 is a top plan view of the base of the machine but with the longitudinally movable table mounted thereon;

Fig. 6 is a top plan view of a slide employed;

Fig. 7 is a side elevational view of such slide;

Fig. 8 is an end elevational view of such slide;

Fig. 9 is a top plan view of a slight modification of the slide as used in profile grinding;

Fig. 10 is a top plan view of a modified form of the machine adapted for use in profile or contour grinding;

Fig. 11 is a front elevational view of the machine of Fig. 10;

Fig. 12 is a sectional view taken substantially on the plane of the line 12—12 of Fig. 11;

Fig. 13 is a sectional view taken substantially on the plane of the line 13—13 of Fig. 11;

Fig. 13A is a detail view at right angles to Fig. 16;

Fig. 14 is a detail elevational view of a portion of a crank means employed, the view being taken as on the line 14—14 of Fig. 1;

Fig. 15 is a front elevational view of a bench

2

or pedestal type of machine for multi-angle grinding;

Fig. 16 is an end elevational view of the machine of Fig. 15, the view being taken as looking from the right in said figure; and

Fig. 17 is a detail view showing an adjustable stop employed for one of the swivels.

The base, bed and table structure is the same in the machine of Figs. 9 through 13 as in the machine of Figs. 1 through 8 and 14 and such structure will first be described and thereafter the machine of Figs. 1 through 8 and 14 will be specifically considered.

The machine of the present invention is in some respects an improvement on the machine of my prior application Serial Number 493,058, filed August 10, 1943, and which matured as Patent No. 2,389,224, on November 20, 1945.

Referring at first to the two forms of the invention shown in Figs. 1 through 8 and 14 and Figs. 9 through 13, the machine includes a base 18 adapted to be disposed on a floor or the like and having a bed, generally designated 11, disposed thereon and secured thereto as by bolts 12. Movable longitudinally on the bed 11 is a table generally designated 13. Base 18 includes a basin-like portion about the lower part of the bed 11 and such basin-like portion is defined by an upwardly directed or curved flange 14 about the outer edge of the base.

Bed 11 is generally L-shaped in plan and has its longer portion or arm 15 extending along the front edge of the top side of the base 18 and has its shorter arm or portion 16 extending rearwardly at the right-hand side or edge of said base. Bed portion 16 is of less height than bed portion 15 as best shown in Fig. 3. Bed portion 15 mounts the table 13. To this end the mentioned bed portion is provided in its upper side with a flat way 17 and a V-way 18 (see Figs. 3 and 12) with which cooperate corresponding rail portions 19 and 20 on the underside of the table 13 whereby the latter is mounted for guided longitudinal movement relative to the bed 11. Rollers 21 and 22 are mounted by the bed for supplying lubricant to the portions 19 and 20 of the table.

23 is a stop lug formed or secured on the front face of the bed portion 15 and such lug extends to a position between a pair of adjustable screws 24 and 25 carried by lugs 26 and 27 respectively. These lugs 26 and 27 are mounted on bolts 28 and 29 respectively, having their heads disposed in a V-T slot 30 opening through the front edge of the table 13. Clearly the bolts 28 and 29 may

be adjusted along the slot 30 and then tightened in place and thereafter the screws 24 and 25 may be given careful adjustment so as to engage the stop lug 23 and limit the respective back and forth movements of the table 13 on the bed 11.

Through suitable gearing and a rack a hand wheel 31 at the front of the machine may be used for imparting longitudinal movement to the table 13. Such wheel is fixed to a shaft 32 passing through the front wall of the bed 11 and within said bed a relatively small diameter gear 33 is fixed to the shaft and meshes with a larger gear 34 fixed along with a small diameter gear 35 to a jack shaft 36. Gear 35 meshes with a larger diameter gear 37 fixed to a shaft 38 meshing with the teeth of a rack 39 fixed to the underside of the table 13 and extending longitudinally of the latter.

With this gearing arrangement it will be clear that very fine adjustments or movements may be imparted to the table 13. A substantial movement of the hand wheel 31 will result in but a slight feed of the table and the latter may be moved back and forth with a smooth steady motion in either direction depending on the direction of movement of the hand wheel. For my present purpose a smooth steady movement of the table 13 is needed and the described gearing provides the means for accomplishing the desired results. However, it is to be understood that the invention is not limited to the feeding of moving of the table 13 by a means including the gearing described as other means (such as that disclosed in my above identified application) may be used for this purpose.

Optionally operable means are provided for locking the table 13 against any movement on the bed 11 in any desired position of adjustment of the table. Such means includes a pair of spaced brackets 40 and 41 of generally L-shape secured to the underside of the table with their depending arms in alignment. A bar 42 has its ends rigidly mounted in the depending arms of these brackets and the brackets are mounted to have the bar 42 parallel with the plane of movement of the table. To this end shims may be used to properly position the brackets or other means providing for adjustment may be used. Screws 43 are shown as securing the brackets 40 and 41 in place.

A locking means or lug 44 has an opening slidably receiving the bar 42 and from such opening the said lug is split to its upper edge (see Figs. 5 and 12). A bar or shaft 45 has a hand piece 46 secured to its outer end portion and then passes through the front or forward wall of the bed 11. Said bar has its inner end threaded to the split portion of the lug or means 44 in such manner that on turning of said bar in one direction the split portions of the lug are drawn toward one another whereby to reduce the size of the opening through which the bar 42 passes and squeeze said bar and hold it against movement.

Thus on tightening of the lug 44 the bar 42 is locked in position and as said bar is fixed to the table 13 the latter is locked against any movement relative to the bed 11. Turning of the hand piece 46 in the opposite direction opens the lock lug 44 permitting of movement of the bar 42 therethrough and thus of movement of the table 13 on the bed 11.

It is noted that the clamping of the bar 42 by the lug 44 takes place in such manner that the bar is drawn slightly downwardly forcing the V-shaped rail or means 20 of the table into the

V-shaped way 18 of the bed 11. Thus there is no lateral or longitudinal movement of the table as it is locked and no disturbance of any careful adjustment that has been made.

It is noted in Figs. 1, 3 and 11 that the table 13 may be adjusted to have an end portion disposed over the forward end of the portion 16 of the bed.

The machine of Figs. 1 through 8 and 14 I refer to as a multi-angle grinder and the same, in addition to the base, bed and table above described, includes a work head generally designated 47 and a tool head generally designated 48. Work head 47 is mounted for swivel adjustment on a manually operated slide generally designated 49 and the latter is in turn mounted for swivel adjustment on a base member 50 secured on the table 13 and adapted to be adjusted in the direction of the length of the latter.

In its upper side table 13 is provided with a longitudinally extending V-T slot 51 and the base member 50 includes a plate portion 52 disposed on the upper side of the table and having a pair of bolts 53 passing therethrough and having their heads disposed in said slot (see Figs. 1, 4, 7 and 8). The bolts 53 also pass through elongated keys 54 secured to the under side of the plate portion 52 and of substantially V-shape and partly entering the slot 51.

Screws 55 secure the keys 54 to the plate portion 52 and the keys serve to guide adjusting movements of base 50 on the table and to keep the base against casual movement relative to the table. Clearly on loosening of the nuts 56 the base member 50 and all parts mounted thereon may be shifted longitudinally of the table and after proper and desired adjustments have been made the nuts 56 are tightened forcing the V-shaped keys 54 tightly into the V-shaped portion 40 of the slot 51, the heads of the bolts 53 being drawn against the outer walls of the T-shaped portion of the slot. In this way the base member 50 and all parts thereon may be adjusted along the table and rigidly secured to the table in any desired position of adjustment relative thereto.

In addition to the plate portion 52 the base member 50 includes a raised or thickened central portion 57 graduated about its upper edge as shown at 58. Opening through this thickened or central portion of the base member 50 is an annular socket 59 (see Fig. 4) concentric or at least substantially concentric with the outer graduated upper edge of such portion 57. As shown socket 59 is slightly tapered being of greatest diameter at its upper end.

Socket 59 receives a tapered pilot 60 integral with and depending from the lower side of a swivel slide 61 forming a portion of the slide generally designated 49. Such slide 49 (see Figs. 4, 6, 7 and 8) includes a bottom cover plate 62 having a tapered opening therethrough and through which the pilot 60 has a snug fit before passing into the socket 59.

Pilot 60 includes upper and lower portions 63 and 64 (see particularly Fig. 4) bearing against the side walls of the socket 59 whereby the slide 49 is adapted to be turned or swivelly adjusted on the base member 50. Intermediate such bearing portions 63 and 64 the pilot is undercut or cut away to provide a portion having an inclined or tapered wall 65 of smallest diameter toward the upper end of the pilot and tapering into the bearing portion 64.

Securing bolts 66 pass through radially dis-

posed openings in the base member 50. These bolts may be threaded inwardly and outwardly, radially, of the base member. The inner flat ends of bolts 66 bear on the outer flat ends of binder pins 67 journaled in reduced diameter portions 68 of the radially disposed openings and enter the socket 59 at a point to engage the inclined wall portion 65 of the pilot 60. From this it will be understood that on tightening of the bolts 66 their inner end portions will force the binder pins 67 against the wall portion 65 and with a cam-like action tend to draw the pilot 60 into the socket 59.

The result of this action is that the swivel slide 61 is drawn down tight against the cover plate 62 which in turn is drawn tight against the upper portion of the raised or thickened central portion 57 of the base member. Thus the said slide portion will be held against any casual movement, turning or otherwise, relative to base 50. On slight loosening of the bolts 66 the pilot 60 and thus the entire slide 49 may be turned or adjusted relative to the base member 50.

Preferably the cover plate 62 is provided with a mark 69 to be read in connection with the graduations 58 on the upper central portion of the base. With the described arrangement when the bolts 66 are tightened there is no tendency to disturb any adjustments that have been made as the tightening of the bolts does not tend to turn or rotate the pilot 60 in the socket 59. While four bolts 66 have been shown it will be understood that the number may be varied.

The cover plate 62 is a relatively stationary part of the slide 49 and in eccentric relation with the pilot 60 is pinned or otherwise secured or made rigid with the swivel slide 61 as by a pin 70. Slide 49 includes a relatively movable or reciprocable portion 71 adapted to be reciprocated on the swivel slide 61 as will appear. Part 40 or portion 71 rests or bears downwardly on the swivel slide 61 as on the flat surfaces 72 and 73 (Fig. 4) as the edges of the part 61 and the inclined surfaces 74 and 75 immediately inwardly of the portions 72 and 73. Also there may be 45 engagement between the parts at 76.

The construction is such that the width of the portions 74 and 75 measured horizontally is the same or greater than that of the portions 72 and 73 measured the same way. Thus owing to the fact that the portions 74 and 75 are inclined they present a greater area for wear than do the portions 72 and 73. It is therefore planned to have the wear in the portions 74 and 75 take place at the same or less rate than in the portions 72 and 73.

In explanation of this it is noted that if slide 71 was raised a slight distance with respect to the swivel slide 61 and the distance between the bearing surfaces 72, 73, 74, 75 and 76 of the named parts are measured normal to said surfaces it will be found that the distance at bearing surfaces 72, 73 and 76 are equal to each other and the distances at surfaces 74 and 75 are equal to each other but less than the distances at surfaces 72, 73 and 76.

Therefore it will be understood that a given amount of wear of the inclined surfaces 74 and 75 tends to lower the slide 71 a greater distance than the same amount of wear in the horizontal surfaces 72, 73 and 76. The actual ratio depends on the angle of the surfaces 74 and 75. From the above it will be clear any wear in the respective bearing surfaces will result in surfaces 74 and 75 coming into tighter contact but that owing

to the relation of the areas of surfaces 74 and 75 with those of surfaces numbered 72 and 73 all surfaces will remain in contact and wear evenly and that the surfaces 74 and 75 prevent any relative movement of slide 71 on the swivel slide 61. The contact at 76 provides for a locking feature as will appear.

With the described construction it will be understood that wear will not develop in any such manner as to permit of lateral movement of the slide 71 relative to the swivel slide 61 or in any such manner that one side of the slide part 71 will be lower than the other side thereof. Therefore the slide part 71 is always mounted perfectly horizontally and against any but a reciprocating movement on the swivel slide 61. Further with the described construction the occasion for a gib or other means of adjustment or to compensate for wear as between the reciprocable slide and the swivel slide is eliminated.

A pair of side strips 77 and 78 are secured by screws 79 to the lower longitudinal edges of the movable slide part 71 and entering under the lower edge portions of the swivel slide 61 serve to assist in guiding movements of the part 71 and prevent any vertical movement of said part relative to the swivel slide. Part 71 has relatively heavy pieces 80 and 81 secured to its respective ends by screws 82 and these end pieces are located beyond the ends of the swivel slide 61.

Screws 83 secure closure plates 84 and 85 to the lower edges of the end pieces 80 and 81 respectively, and such plates extend from said end pieces toward one another and serve to prevent the entrance of dust into the ways or bearing surfaces between part 71 and swivel slide 61. As seen in Fig. 7 the plate 84 is closing the space between end piece 80 and the adjacent end of cover plate 62 while plate 85 is entered over the other end portion of said cover plate. On movement of the slide part 71 toward the right in said figure plate 85 will be exposed and will serve to exclude dust from entering between end piece 81 and the adjacent portion of the bottom plate 62 while plate 84 will move in over the adjacent end portion of the bottom plate.

Coil springs 86 disposed in sockets 87 in the swivel slide 61 bear against rods or plungers 88 bearing against the end piece 80 and constantly tend to maintain the slide part 71 in the positions of Figs. 6 and 7. A screw 89 adjustable through end piece 81 is adapted to engage a stop projection 90 on the swivel slide 61 whereby to limit movement of part 71 by said coil springs. A lock nut 91 is provided to secure said screw after any adjustment thereof. A second screw 92 is threaded through end piece 80 and is adjustable therethrough and is adapted to engage the adjacent end portion 93 of swivel slide 61 to limit movement of part 71 on said swivel slide in opposition to the coil springs 86. Screw 92 is provided with a lock or jam nut 94 for securing it in adjusted position.

Means are provided for manually moving the slide part 71 against the tendency of the coil springs 86 and as will later appear the slide with slight modifications is adapted to be moved by a cam against the tendency of said springs when the slide is used in a profile grinding operation and by a crank means in certain grinding operations. The manual means shown includes a lever 95 pivoted intermediate its ends at 96 and at one end pivoted at 97 to the free end of a link 98 which in turn is pivoted or anchored by a pivot

99 on a lug 100 supported by and disposed laterally of the bottom plate 62 of the slide.

Pivot 96 enters a slight boss 101 on one end portion of the upper side of the slide part 71 and at opposite sides of said boss the part is provided with bearing surfaces 102. At times it is desirable to reverse the position of the lever 95 and to provide for the pivotal mounting of the lever in reversed position a boss 103 is provided on the upper side of slide part 71 toward the end thereof opposite that at which the boss 101 is located.

With the described construction it will be clear that (see Fig. 6) on pulling of the free end of the lever 95 toward the slide part 71 will be moved on swivel slide 61 in opposition to springs 86 compressing the latter between the forward ends of the plungers 88 and the inner ends of the sockets 87. On release of pressure on the lever the springs will act to return slide part 71 to normal position with the screw 89 against the stop projection 90. The slide part 71 is provided on each longitudinal edge with a finished surface 104 against which a sine bar or the like may be used when adjusting the slide to various angular relationships with the table 13.

When the slides are used in multiple (as will later appear) it is sometimes necessary or at least desirable to lock one slide against casual movement while the other slide is being manipulated. The reasons for this will appear. To the desired end, it is noted that swivel slide 61 is provided with a central longitudinally extending inverted T-shaped slot 105 in which is located the head of a bolt 106 extending through the upper side of the slide part 71 and there provided with a nut 107. Clearly bolt 106 is movable with the slide part 71 and this part may be secured in fixed relation with the swivel slide 61 on tightening of the nut 107 to clamp part 71 against the bearing surface portion 76 of swivel slide 61. The nut may be tightened to secure the parts against relative movement with the head of bolt 106 in any position of adjustment along the length of the slot 105.

Slide part 71 is built up centrally on its upper side providing a portion 108 having a tapered opening or annular socket 109 therein corresponding exactly with the socket 59 in the base member 50. About its outer edge portion the slide part 71 is graduated as shown at 111 in the manner described in connection with the graduations of the base member 50. Socket 109 is for the reception of a projection (not shown) on the lower side of the body portion 113 of the work head 47. Such projection is of the identical construction with the projection or pilot 60. For the purpose of securing the projection or pilot body 113 in the socket 109 and clamping the lower side of the body 113 against the upper side of the raised central portion 108 of the slide part 71, four bolts 114 are threaded radially through such portion and these bolts function with pins 115 as and for the purpose set forth when considering the bolts and pins 66 and 67 respectively.

Work head 47 in addition to the body 113 and at the lower end of the latter includes a flange-like portion 116. The described pilot or projection depends centrally from the lower side of this flange and is preferably concentric therewith and fits in the socket 109 in the same manner as the pilot 60 fits in the socket 59 first described. Thus work head 47 is turnable relative to the slide 49 on loosening of the screws 114 and the flange 116 of the head is provided with a mark 117 to

be read in connection with the graduations 111 about the upper edge of the raised central portion 108.

Mounted on the upper side of body 113 is an electric motor 118. Said body is bifurcated in its upper portion whereby it comprises spaced sleeves 119 and 120. Suitable bearings are provided in said sleeves or sleeve-like portions and while said bearings are not herein disclosed they are fully disclosed in my co-pending application above identified. A spindle 121 extends through said bearings and at its forward end mounts a chuck 122 for holding work 123. Extending through the spindle 121 is a quill 124 and at its end opposite said chuck the quill is provided with a hand wheel or the like 125 for manipulating the quill to thereby open and close the chuck. Nuts 126, 127, 128 and 129 are for effecting adjustments of the bearing means (not shown) and are used as fully set forth in my application above identified.

A bracket 130 is secured to the upper side of the body 113 as by bolts 131 passing through longitudinally extending slots in the bracket. With this arrangement it will be clear that, within the limits of the lengths of the slots, the bracket 130 may be adjusted relative to the body 113. At its rear end the bracket supports a bearing means 133 rotatably supporting a shaft 134 having stepped pulleys 135 and 136 fixed thereto to turn therewith. On the shaft of motor 118 is a stepped pulley 137 and a belt 138 drives the pulley 135 from the pulley 137.

Fixed on the rear end portion of the spindle 121 is a stepped pulley 139 and a belt 140 drives said stepped pulley 139 from the stepped pulley 136 on the shaft with the pulley 135. Thus it will be seen that the motor 118 drives the spindle 121 and the chuck 122. By shifting the belts 138 and 140 to different steps of the pulleys various speeds may be imparted to said spindle and chuck. Any slack in the belts may be taken up by adjusting the bracket 130 to carry the pulleys 135 and 136 away from the pulleys 137 and 139 and by adjusting the motor 118 on the motor base either 45 toward or away from the pulley 135 as is required to complete adjustment and finally securing the motor in position by the bolts 142. A control switch S is mounted near the forward portion of bracket 130. 143 is a portion of a means (fully disclosed in my prior application) for holding the spindle 121 against turning movement while using the hand wheel 125 with standard draw back chucks, etc.

Referring now to the tool head end of the machine the bed portion 16 is provided in its upper side with forwardly and rearwardly extending ways 144. Slidable on the ways 144 is a carriage generally designated 145 and comprising a base portion 146 having an undercut or dove-tail portion 147 movable in the ways 144. A gib 148 is provided in the ways between the slide or carriage and the bed portion 16 and the said gib is adjustable by means of screws 149 to take up any play caused by wear in the dove-tail surfaces.

Carriage 145 is of some height and has a pair of spaced keys 150 secured to its upper side by screws 151 and in addition a pair of T-bolts 152 pass through the upper portion of the slide and have their heads disposed in the inner portion of a V-T slot 153 in the underside of a horn-like projecting portion or member 154. The keys 150 enter the V-portion of the slots 153 and when the nuts 155 on the bolts 152 are loosened the horn or member 154 may be adjusted in the di-

rection of its length which is transversely of the entire machine. The keys 150 assist by guiding such adjustment movement and on tightening of the nuts 155 the member 154 is drawn downwardly onto the wedge or V-shaped keys 150 and is securely locked in any desired adjusted position.

Means are provided for adjusting the carriage 145 forwardly and rearwardly on the ways 144 and as here shown a shaft 156 has bearing in the walls of the bed portion 16 and entering a channel in the dove tailed portion 147 is threaded into a lug 157 depending into said channel and rigid with the carriage 145. On the outer end of shaft 156, at the forward or front side of the machine for convenient operation, is fastened a handwheel 158 by means of which the shaft may be rotated in either direction to feed the carriage 145 forwardly or rearwardly along the ways 144.

The lower portions of the carriage 145 are provided with side and end covers 159 and 160, respectively. These covers act as dust guards to prevent the entrance of dust and grip to the ways and the front end cover is provided with an opening for the passage of the threaded shaft 156. Rotatably mounted on a hub-like portion of wheel 158 is a collar-like member 161 having graduations thereon as shown and which are adapted to be read in connection with a mark 162 on the bed of the machine. Preferably a screw 163 fixes the collar 161 to the hub of the wheel 158 in a desired position of adjustment for ease of reading of the graduations in connection with the mark 162. The collar may be adjusted to have the parts so arranged that any graduation is either the starting point or the stopping point for movement of the wheel for some particular work to be performed.

On the upper side of the horn 154 and toward the forward end thereof is an adjustment limiting device generally designated 164. Such device comprises a member including flanges 165 and 166 and including a ring-like lower part entering a counterbore 167 in the upper side of the horn. Bolts or screws 168 secure the member to the horn against turning movement and the ring-like lower part entering counterbore 167 prevents any lateral movement of the member on the horn. Flange 166 is of greater diameter than flange 165 and is provided at its opposite sides with arcuate slots receiving the bolts 169 adapted for adjustment within the limits of said slots.

A tapered socket 170 in the assembly 164 receives a projection 171 corresponding with pilot 60 except that pilot 171 need not be provided with the inclined portion shown at 65 on the pilot 60. Pilot 171 is part of the swivel slide of a slide generally designated 172 and disposed on the device 164 and particularly on the plate 165 of the latter. Slide 172 is similar to the slide 49 above described in detail but the slide 172 includes a heavy bottom member or plate 173, through which the pilot 171 passes. Slide 172 does not employ the adjustable screws 89 and 92 and a slightly different end plate is used at one side of the slide 172 from that of slide 49. The movable part 174 of slide 172 is centrally built up but is not graduated. Coil springs 66 in slide 172 function to bias slide part 174 in one direction so that any play occurring about the pins 221 and 234, due to wear, will all be in one direction. Thus the springs serve to keep the pins each against one side of its hole in the pitman so there is no free movement of the latter such as would

otherwise take place and cause a clicking noise and result in vibrations that would be transmitted to the grinding wheel.

A bolt 175 is made rigid with the pilot 171 by means of a binder screw 175a and passes downwardly through the horn 154. Surrounding the bolt 175 as it passes through the horn is a sleeve 176 adapted for slight vertical movement but held against turning movement by a screw 177. At its lower end the sleeve 176 has a recess receiving the head of the bolt 175 and threaded onto the sleeve below the horn is a nut 178 provided with a manipulating handle 179 projecting to one side of the machine for convenient use.

As the nut 178 is turned in one direction it will (since the nut bears against the underside of the horn 154) draw the sleeve 176 downwardly. The sleeve bears on the head of the bolt 175 so the latter will be drawn downwardly and will draw the pilot 171 into the socket 170. Further the bottom plate 173 of slide 172 is drawn tight against the upper side of the plate 165 thus securing the slide against turning movement with the pilot as an axis.

Stop or limiting lugs 180 and 181 are provided on the under side of slide bottom plate 173 in position to have one of such lugs engage one of the bolts 169 when the slide 172 is turned with the pilot 171 as a center. When the position of the slide is to be thus adjusted the nut 178 is loosened and the slide turned until one of its stop lugs engages a previously adjusted and positioned bolt 169 whereupon the nut 178 is again tightened to secure the slide in its new adjusted position at some chosen angle to the center line of the horn 154 or the table 13, etc.

A socket 182 in a swivelling means 185 is concentric with a flange 185 and receives a pilot 183 integral with an upper projection 184 of the reciprocable slide 174. Flange 186 is not circular one side or edge portion being cut away whereby to have the flange clear a belt guard 188 later to be described.

Said flange is provided with a pair of spaced arcuate slots 189 and 190 in which are mounted bolts 191 and 192 adapted to be adjusted within the limits of the respective slots and then tightened and thus secured in adjusted positions.

The bolts 191 and 192 provide stops adapted to be engaged by lugs 193 and 194 on the upper side of the movable slide part 174. Means or body 185 is provided with an annular socket opening through its underside and receiving the projection 184 whereby the body or means is turnable about said projection as a center. It will be understood that depending on the positions of the bolts 191 and 192 in the arcuate slots of the flange 186 the turning movement of the means 185 about the projection 184 is limited.

Body 185 includes or mounts a spindle quill receiving means 195 in which is located the spindle quill member 196 mounting the spindle 197 to the forward end of which is detachably connected the shank 198 of a grinding wheel 199. On the upper portion of a bracket-like extension 200 of the body 195 is supported a bracket 201 secured in place by a bolt 202 and mounting an electric motor 203 shown as bolted to the said bracket but which may be secured thereto in any desired manner. A belt 204 enclosed in the housing 188 is trained over pulleys 205 and 206 on the shaft of motor 203 and the spindle 197 respectively whereby said motor drives said spindle. Housing or guard 188 is adjustably support-

ed on a bracket or plate 207 carried on the outer end of a rod 208 secured to bracket extension 200 by a bolt 209.

A vertical annular bushing 210 is rigid with the body or means 185 and passes downwardly therethrough and through said bushing passes a bolt 211 having its lower or inner end threaded into the projection 183 and 184. A handle 212 is provided for tightening and loosening of the bolt 211 and on tightening of said bolt the body 185 is drawn downwardly on projection 184 whereby the said projection 183 is tended to be moved more into the socket 182 receiving it and thus wedging or clamping the said body and all parts carried thereby or mounted thereon against turning movement on said projection.

Clearly the bolt 211 is concentric with the projection 184 and bushing 210. On manipulation of the handle 212 to loosen the bolt 211 the body 185 and parts carried thereby or mounted thereon may be turned with said bolt as an axis or center, a handle 213 being provided for that purpose. In the use of the machine the bolts 191 and 192 in the arcuate slots of the flange 186 by engagement with the stop lugs 193 and 194 control the extent of turning movement of the body 185 on the projection 184.

While the slide 172 is internally the same as the slide 49 means are provided for mechanically reciprocating the movable part 174 of the slide 172. Thus a bracket 214 is secured by screws 215 to the underside of the bottom plate 173 of the slide 172 and mounts the reciprocating means now to be described. Mounted on the upper side of bracket 214 is an electric motor 216. A bracket extension 217 includes a bearing portion 218 mounting a shaft 219 having a stepped pulley 220 thereon.

Also mounted by the bracket 214 is a shaft 221 extending parallel with the shaft 219 and the shaft of the motor 216 but disposed below and inwardly of the latter. Fixed on the shaft 221 is a pulley 222 and a stepped pulley 223 is fixed on the shaft of the motor 216. Through a belt 224 trained over pulleys 223 and 220 the motor 216 drives the pulley 220 and a belt 225 trained over the latter pulley and the pulley 222 provides means whereby the shaft 221 is driven from the motor 216.

Shaft 221 has bearing in a wall portion 226 of the bracket 214 and at the inner side of said wall is integral with or rigidly connected in concentric with a head 227 having a T-slot 228 extending thereacross. A T-bolt 229 has its head in the slot 228 and a bushing 230 is located on the shank of said bolt between the head 227 and a washer 231 held against the bushing by a nut 232. Thus the nut may be tightened on the bolt without binding a pitman 233 at one of its ends receiving the bushing 230 and held thereon by the washer 231.

At its other end the pitman 233 is pivoted at 234 to an end plate or member 235 (substituted for end 81 of slide 49) of the movable part 174 of the slide 172. With this construction it will be understood that when the motor 216 is operating and the bolt 229 is in eccentric relation to the shaft 221 the movable slide part 174 will be reciprocated on the swivel slide of the slide 172. On loosening of the nut 232 the bolt 229 may be adjusted along the slot 228 to change the relation of the bolt to the shaft 221 and by locating the bolt more or less in eccentric relation to such shaft change the throw of the slide part 174. As the entire tool head 48 is mounted on the

slide part 174 it will be clear that such head and the grinding wheel 199 carried thereby will be reciprocated by the motor 216 when the latter is operating. The bracket 214 is provided with a loop portion 235 to serve as a handle for turning the slide 172 on the means 164 when the nut 178 has been loosened.

When using the machine the proper tool 199 with the proper spindle or shank 198 having been chosen and mounted in the tool head 48 the work 123 is secured in the chuck 122. If a straight hole is to be ground the parts are all in alignment as shown and the nut 107 is tightened to secure the slide part 71 against casual movement on the slide part 61 and all the described structures for swivel adjustments are locked against casual movement. The machine being set the wheel 31 is used to feed the table 13 to carry the work to the grinding wheel 199. The work is being rotated by the motor 118 and the grinding wheel in addition to being rotated by the motor 203 is being reciprocated by the motor 216.

As the work is ground away and/or as the wheel 199 wears the tool head is adjusted transversely of the machine by manipulation of the head wheel 158 to feed the carriage 145 and thus the tool head transversely of the machine. Generally the table 13 will be fed back and forth until little if any cut is being made and then the adjustment will be made by manipulation of wheel 158. Instead of using the table 13 for the grinding of a straight piece or a straight sided hole in a piece the table may be locked against movement by manipulation of the hand piece 46 and the nut 107 loosened so that the work may be moved back and forth through manipulation of the handle or lever 95 to move the movable part of slide 49.

For each job the parts of the machine are so positioned relatively that the grinding wheel is reciprocated in a path parallel with the path of feed of the work and parallel with the surface being ground. Thus, for example, if a part to be ground includes a bevelled surface followed by a straight sided surface the slide 49 is adjusted on its swivel until it is disposed at an angle to the table 13 equal to the angle of the bevelled surface to be ground. Then the slide is locked in place and the work head 47 adjusted on its swivel to position the work parallel with the line of movement of table 13 and the work head is locked in place against casual movement. At this time the table 13 is secured against casual movement by tightening of its lock through manipulation of part 46.

Now one bolt 169 is adjusted and secured in such position in its arcuate slot in part 166 that when the bolt is engaged by stop lug 180 the slide 172 is parallel with the line of movement of table 13. Then the other bolt 169 is adjusted in its arcuate slot to a position such that when it is engaged by stop lug 181 the slide 172 is parallel with the contemplated path of movement of previously adjusted slide 49. Indicating means may be used in setting the bolts 169. On loosening of nut 178 the slide 172 (and the tool head 48 mounted thereon) may be swung to engage either of its stop lugs 180 and 181 with the preset bolts 169.

Adjustments having been made as above set forth nut 178 is loosened and the slide 172 swung to bring its lug 181 against a preset bolt 169 and then the nut 178 is tightened. Slide 172 is now positioned so that it (and the grinding wheel) are reciprocated from motor 216 in a path

parallel with the path in which slide 49 is set to be moved by its handle or operating lever 95. Through manipulation of wheel 158 the tool head may be adjusted back and forth to properly locate the grinding tool and by adjustment of table 13 (part 46 having been turned to release the table) the work is advanced to be engaged by wheel 199 and then the table is locked in position.

The set-up is now complete and the slide 49 is manipulated moving the work across the grinding wheel at a preset angle. At the same time the grinding wheel is being rotated and also, by motor 216, is being reciprocated with the slide 172 and the latter has been so set that the grinding wheel is being reciprocated in a line parallel with the path of movement of slide 49 and parallel with the surface being ground. Thus there is no tendency of the wheel to dig into the work. Removal of stock from the work and wear of the wheel is compensated for by adjusting carriage 145 through manipulation of hand wheel 158.

When the bevelled surface of the work has been properly ground nut 178 is loosened and the slide 172 swung to engage its stop lug 180 with its previously set bolt 169 bringing the slide 172 back into parallel relation with the table 13. Then nut 178 is tightened and the slide 49 is secured in retracted position by nut 107. Any necessary lateral adjustment of the tool head is made by moving carriage 145 and the table 13 is released by turning of part 46 and then is fed to carry the work to and from the tool head by turning of wheel 31. In this way the straight sided surface is ground. When the part is finished it may be duplicated readily since the stop bolts 169 are located and the slide 49 is set for movement in the correct path for the bevelled surface to be ground.

For grinding a bevel deep inside a hole a somewhat different set-up is used. Such a piece of work is shown in Fig. 2A and there the part designated 328 has an opening therethrough including a straight side wall portion 328 and a bevelled portion 330 deep in or within the opening and then a smaller diameter straight sided portion 329a. There the grinding wheel 331 is mounted on a spindle 332 and includes a straight sided body portion 333 and a bevelled forward end portion 334, the bevel being at the angle of surface 330.

When setting-up for this job the slide 49 is adjusted on its swivel mounting to dispose it at an angle to the table 13. The swivel mounting of the slide is then locked with the slide positioned for movement relative to the table in a path parallel with the surface 330 to be ground. Next the work head 47 is adjusted on its swivel mounting to dispose the work with its surface 329 parallel to the path of movement of the table 13. At this time stop 180 is in engagement with its bolt 169 so the slide 172 and spindle 332 are both parallel with the path of movement of table 13.

Then, suitable indicating means being used, the nut 178 is loosened and the slide 172 positioned so that when its stop lug 181 is against its bolt 169 (the latter having been adjusted in its arcuate slot) the said slide 172 is positioned for reciprocation in a path parallel with surface 330 to be ground. The bolt 169 is tightened in place with lug 181 against it.

Next bolt 191 may be adjusted in its arcuate slot to so position it that when it is engaged by stop lug 193 the tool head 48 is disposed with

spindle 332 parallel with table 13. Then handle 212 is manipulated to release the tool head and it is swung to bring the spindle 332 back into parallel relation with table 13 and bolt 192 is adjusted in slot 190 to bring it against the stop lug 194 and then said bolt is tightened to lock it in position. Now bolt 169 is located for engagement by lug 181 and bolt 192 is located for engagement by lug 194. Then the tool head and the slide 172 are swung back until lug 194 engages its bolt 191 and lug 180 engages its bolt 169 and levers 179 and 212 manipulated to clamp the named parts against casual movement.

It will be noted that at this time the spindle 332 and the center of the work piece are both parallel with the table 13. Now the work may be moved forwardly with the table and the tool head may be adjusted crosswise with respect to the table to engage the side portion 333 of the wheel 331 with the surface 329 of the work. The table is fed back and forth to grind the surface 329 and removal of material from the work and wear of the wheel is compensated for by feeding carriage 145 crosswise with respect to the path of movement of table 13. During this grinding operation lugs 180 and 193 being in engagement with bolts 169 and 191, respectively, the slide 172 and thus the wheel 331 are being reciprocated in paths parallel with the path of movement of the work and there is no digging of the wheel into the work.

When surface 329 is completed the handles 179 and 212 are shifted to release the slide 172 and the tool head 48 and their swivel mountings and they are swung to bring stop lug 181 of slide 172 against the previously set bolt 169 and the lug 194 of the tool head against the previously set bolt 194. This positions the wheel 331 with its body portion 333 parallel with the work surface 329 and its portion 334 parallel with the work surface 330. At the same time the slide 172 is positioned to reciprocate in a path parallel with said work surface 330 and the tool head and slide are secured in adjusted positions by moving levers 179 and 212.

Now the table 13 may be fed to carry the work toward the tool and the carriage 145 may be adjusted to position the tool to enter the work and by movements of the table and carriage the work and tool are brought into relation with the tool, portion 334 in engagement with the work surface 330. The various motors may be started if they are not already in operation and the work and tool will be rotated and in addition the tool and its spindle will be reciprocated more or less sidewise but in a path parallel with the surface 330 owing to the setting of the slide 172 and tool head 48 with its stop 181 against the preset bolt 169 and its stop lug 194 against the preset bolt 192.

Thus reciprocation of the tool does not result in it digging into the work. At this time table 13 is locked against casual movement and nut 107 released to permit of movement of slide 49 by lever 95 and such movement will take place in a path parallel with surface 330 since the slide was previously set. As the tool is reciprocated with slide 172 the tool is carried back and forth as between the dotted line positions of Fig. 2A (although it is noted that the reciprocating stroke of slide 172 is not in practice sufficient to move the wheel the distance shown between the centers of the dotted line positions of the wheel in Fig. 2A) the plane of the path being indicated by arrow 335 while the plane of the path of

movement of the work with slide 49 is indicated by the parallel arrow 336.

Next the straight sided hole portion 329a is to be ground. To accomplish this the handles or levers 179 and 212 are loosened and the slide 172 and the tool head 48 swung on their swivel mountings to bring their stop lugs 180 and 193 into engagement with the preset bolts 169 and 191, respectively. This locates the reciprocable slide 172 and the spindle of the grinding wheel 331 in parallel relation with one another and the table 13. Now carriage 145 may be adjusted to shift the tool transversely of the line of movement of the table since hole 329a is of smaller diameter and then the proceedings are as described in connection with surface 329.

That is nut 107 is tightened to secure slide 49 against casual movement and table 13 is used to feed the work past the tool. When the piece of work has been finished it may be easily duplicated since the bolts 169, 191 and 192 have been set and locked in positions and the same is true of the slide 49. In the foregoing description of the operation as applied to two particular jobs certain steps have been given in considerable detail. However, it is to be noted that the stop bolts are adjusted one to position slide 172 for each of the two surfaces to be ground and that either bolt will be used for any particular surface as may be most convenient for any particular job in hand.

In any grinding operation the motor 216 may be stopped and the slide 172 locked against casual movement on tightening of its nut 107. Wheel 158 may be used to move the carriage 145 not only to adjust the tool or grinding wheel for wear or as the work is ground away but also to determine the position of the work head relative to the tool head for any given job. Further the horn 154 may be adjusted on the carriage to dispose the tool head to one side or the other of the center line of the table 13 as may be required for different jobs. When the slide 49 is being manually manipulated its stroke is preferably preset by adjustment of the stop screws 89 and 92.

The present machine is useful in the grinding of cemented tungsten carbide dies as well as dies and other objects and devices of metals and alloys. The machine may be used for grinding, lapping, and honing or polishing operations and while it will rapidly grind cemented tungsten carbide it will also grind tool steel and the like as well as relatively soft metals and alloys such as alloys containing copper, lead, tin and graphite.

The machine will grind to a mirror finish and with an accuracy to give the extreme precision required in die work and the like. There is no bell-mouthing of the work and with a new and fine grain wheel the work may be completed to a mirror finish without changing of wheels or the substitution of a different tool. Further the machine of the invention makes for long life of the grinding wheels used.

That is with a given wheel, of the proper type, the present machine will produce more work than any machine heretofore available. This is probably due to the fact that the machine provides for reciprocation of the wheel while it is at work. The reciprocation of the wheel in the manner herein disclosed provides such relative movements of the wheel and work that various faces of the diamond or other grit used are brought into active use even though such faces may not be so located in the bond as to do their best

cutting if the wheel and work are merely rotated and there is no relative reciprocation.

Once the machine is set up for any given job whether such job involves but a single straight surface to be ground or whether the job involves the grinding of a plurality of angularly related surfaces no adjustments need thereafter be made except the feeding of the carriage 145 and thus the grinding wheel to compensate for wheel wear and to keep the wheel against the surface being ground as such surface is ground down.

The reciprocating motion of the grinding wheel is used for grinding, lapping and polishing on either multi-angle, straight or tapered jobs. The machine is easy to operate, a new operator being readily taught the various adjustments and the "feel" of the machine being readily grasped. All cutting edges of the grinding wheel are utilized as above set forth and the work is accomplished with the utmost precision and without scoring or the making of flats in the work or bell-mouthing of round holes.

The grinding wheel is rotated at a very high speed as, for example, a one-half inch wheel grinding a five-eighths inch hole is rotated in the neighborhood of 50,000 revolutions per minute. The rate of rotation of the work bears a relation to the rapidity of the strokes of the grinding wheel. At present the best results are to be obtained when the rate of rotation of the work being ground, compares with the speed of reciprocation of the grinding wheel in such relation that for each approximately 93 percent of a revolution of the work the wheel is given one complete reciprocation. Such relationship of the motions and speeds of the work and grinding wheel gives work of a mirror finish and serves to remove the material being ground, at a rapid rate. The present method permits of the use of the mentioned high rate of speed of the grinding wheel.

The figure of 93 percent of a complete revolution of the work for each complete reciprocation of the grinding wheel is not absolutely critical. Excellent results are obtained in the range of from 55 percent of a revolution of the work to 128 percent revolutions of the work for each complete reciprocation of the grinding wheel. Results better than those obtained through conventional grinding methods have been obtained in ranges as wide as 43 percent to 143 percent revolutions of the work per a complete reciprocation of the grinding wheel.

However, as the range widens, up or down from 93 percent of a revolution of the work for each complete reciprocation of the grinding wheel, the same excellent results are not obtained and below and above the extreme ranges above given the results are not good as there is a heating of the work, rapid wheel wear for material removed, and a mirror-like finish is not obtained.

The rate of reciprocation of the wheel must be kept in relation to the rate of revolution of the work head. If the wheel is reciprocated too fast, as, for example, if the wheel is given four reciprocations, for each revolution of the work, the results are not satisfactory as the wheel life is reduced because of the breaking down of the bond and the loss of the cutting diamonds. Where the reciprocation is too slow relative to the rate of rotation of the work the action is such that we are getting back toward the conventional way of grinding, which latter is somewhat in the nature of a fine thread cutting action.

I have found that the ratio, between reciproca-

tion of the grinding wheel and rotation of the work, which is best for fast cutting with a rough wheel is also the best for smooth cutting with the finishing wheel when obtaining a mirror-like finish of work. In the operation of the present machine the work is fed along over the grinding wheel. This is a motion in addition to the rotation of the work and the rotation and reciprocation of the wheel.

The relation of the reciprocating motion of the wheel to the rotating motion of the work head is preferably such that any single cutting point on the wheel will not immediately get back into the same path even though the work be only rotated and not fed. This appears to provide for best results even when the work is fed. When the work is fed it will be clear that any particular cutting point on the wheel has no chance of twice entering the same path.

In conventional grinding the tool is moved along the work with the latter and the tool both rotating. Then at the finish the tool is drawn back out of the work and during this return movement tends to cut off or take down most of the ridges formed during the entering movement. With the present method the tool is continually reciprocating and so moves back and forth many times over the same portion of the work as the latter moves over the tool or as the tool moves along the work.

Each of the reciprocating movements of the wheel over the work results in a smoothing out of any high spots or ridges in the work and the net result is a smooth mirror-like finish to the work. The present machine provides for fast cutting of the work and for smooth finishing and these results are in part attributable to the fact that the reciprocation of the grinding wheel brings into active use many more cutting edges of the various diamonds exposed at the surface of the wheel. These results are also obtained because of the pattern established by the relative turning and reciprocation of the work and wheel. Reciprocation of the wheel as disclosed also prevents loading or glazing thereof.

Referring now to the modification of Figs. 9 through 13A the machine there shown is primarily adapted for contour grinding. The base, bed and table structure of this machine is the same as that of the machine first described and has already been considered. In this modification many of the parts are the same as those previously described and where such is the case the same reference characters are used to avoid repeating the description.

In the modification the work head and the tool head are the same as previously described but they are given new general designations and are indicated as 240 and 241, respectively. Work head 240 is mounted on a slide 242 of substantially the construction slide 49 and of the construction of the slide of Fig. 9. Slide 242 is turned 90 degrees with respect to the position of slide 49 of Fig. 1 and so is at right angles to the table 13. Under and mounting the slide 242 is a reciprocable slide 243 of the exact construction of the slide 172 previously described. Such slide 243 is reciprocated by the means previously described and which means has the reference characters heretofore used applied thereto. Thus it will be noted that in effect the slide and work head of the first form of the machine have been raised and the mechanically reciprocable slide from under the tool head of such first form has been disposed under the slide of the work head thereof.

Slide 243 is mounted on the base 50 and the latter is adjustable along the table 13 as has been described.

Referring specifically to Fig. 9 for the details of the slide 242 it is noted that this slide is but a slight modification of the slide 49. The modifications are necessary since slide 242 is used in profile or contour grinding and in Fig. 9 it will be noted that the adjustable stop bolts 89 and 92 have been omitted and that a cam roller 272 has replaced bolt 92 and that in place of bolt 89 a stud 273 has been threaded into or otherwise attached to the projection 90 of the swivel slide 61 and passes outwardly of the slide through its end 81. On the outer portion of stud 273 is a nut 272 adjustable on the stud to limit movement of the slide. With this construction as the slide part 71 is moved on the swivel slide 61 by engagement of roller 272 with a cam or otherwise, the stud 273 remains stationary with the swivel slide and the part 71 moves outwardly toward nut 274.

At the extreme of the movement nut 274 may be tightened against the end piece 81 of the movable slide part 71 and the latter held against the nut by the lever 95 as the table 13 is fed back. This limitation of movement of slide part 71 by nut 274 prevents the slide being moved to such extent as to bring the other side of the work 30 against the grinding wheel 199 and as the part 11 is held against the nut 274 by the lever 95 the work is held away from the grinding wheel during return movement of the table 13. Thus all grinding may be done on one stroke of the table 35 and any back lash or play in the parts will always be in the same direction.

In the modification (see particularly Figs. 10 and 12) the bed 11 includes a portion 275 located in the rear of portion 15 and parallel or substantially parallel therewith. Portion 275 includes an upper surface 276 in which is formed V-T slot 277 receiving the heads of inverted T-bolts 278 and also receiving elongated keys 279. Bolts 278 pass through the base portion 280 of a support 281 whereby the support is adapted to be secured in any chosen position on the surface 276 since the slot 277 extends for the length of such surface. Support 281 includes an upper shelf-like portion 282 having slots 283 therein and on such portion is shown a cam 284 secured in place by bolts 285 passing through the cam and the slots 283. Clearly the cam 284 is adjustably and removably secured to the support.

Suitable dust screens or covers 286 and 287 are disposed below and above the cam to exclude dust and dirt from the roller and the roller engaged surface of the cam. On loosening of the bolts 285 the cam may be adjusted on the shelf-like portion of the support 281 and on loosening of the bolts 278 the support may be adjusted along the surface 276. Following any adjustment the involved bolts are tightened to prevent any casual movement of any of the parts. In adjusting a slide a sine bar may be attached to the finished strips 104 and indicated by an indicator secured in a T-slot 288 in the surface 276 and parallel with the table 13.

Tool head 241 is mounted on a compound slide generally designated 244 and in Figs. 10 through 13A such compound slide 244 has been substituted for the mechanically reciprocated slide of Figs. 1 through 9. Thus slide 244 is mounted on the means or device 164 located on the forward portion of the upper side of the horn 154 and on the upper side of such compensating slide 244 is

mounted the device 185 including the flange 186.

Depending from an annular plate 245 and in face integral with such plate of the slide 244 is a pilot or projection 246 tapered and fitted into the socket in the means 164. On manipulation of nut 178 the said pilot is released or drawn into the socket whereby to permit of swivel adjustment of the compound slide 244 or to secure the latter in any desired adjusted position. Plate 245 is provided with a mark 247 for reading in connection with graduations about the upper edge of the plate 165 of the means 164.

On the upper side of the plate 245 and integral therewith is a body 248 having a longitudinal recess 249 undercut at its opposite sides thus providing dove tail ways 250. On the body 248 is a slide 251 resting on spaced surfaces 252 and having side portions 253 undercut at their outer edges for cooperation with the ways 250. Slide 251 is provided with a longitudinally extending channel 254 opening through its under side. Secured to the upper side of the body 248 and projecting into said channel are spaced members 255 and 256 (see Fig. 13) into the former of which is threaded a feed screw 257 while the latter supports a bar 258 extending in the direction of said screw and said channel.

Members 255 and 256 are secured to the body 248 in any suitable manner and in the drawings they are shown as being held in place by screws. Slide 251 includes end members 259 and 260 as well as side skirt-like portions 261 acting to exclude dust and the like from the ways and from between engaging portions of the slide and body 248. Screw 257 includes an unthreaded portion 262 turnable in a wall of the slide 251 and in the end member 260 thereof and held against movement through said wall by a collar 263 and the hub of a hand wheel 264 made fast with the outer end portion of the screw.

About the hub of said hand wheel is a collar 265 provided with graduations (Fig. 10) adapted to be read in connection with an index mark 266 and which collar is adjustably held in position by a set screw 267. It will now be understood that on turning of the hand wheel 264 the screw 257 will be turned in the member 255, which comprises a nut, and the said screw being held against relative longitudinal movement with the slide 251 the latter will be fed on the body 248, moving along the ways 250. Thus the slide 251 may be adjusted on the body 248.

A bolt 268 passes laterally through the slide 251 and is movable with said slide when the latter is fed along the ways 250. At its outer end this bolt includes a head-like portion 269 comprising a hand piece or knob by means of which the bolt may be manually turned. At its inner end the bolt is threaded into the split portion 270 of a lock-lug 271 through which the bar 258 passes. As the lug 271 is split through from its portion receiving the bar 258 to its upper edge it will be clear that when said split portion is open the lug may move freely along the bar as the lug is moved with the slide 251.

However, on tightening of the bolt 268 the split portions of the lug are drawn toward one another and the lug pinches on the bar securely holding it against movement through the lug. Since said lug is movable with the slide 251 when the latter is being adjusted by manipulation of the hand wheel 264 it will be seen that on tightening of the bolt 268 to have the lug 271 clamp the bar 258 the slide 251 will be locked against movement relative to the body 248, it being borne in

mind that said bar is held by the member 256 and the latter being secured to the body 248. In this form the bottom plate 245 carries the stop lugs 180 and 181 for cooperation with the bolts 169 carried in the arcuate slots in the flange or plate 166.

When using the machine of this modification the cam 284 is chosen according to the contour and size of the part to be ground. With the work held by the chuck and the proper grinding wheel 199 in place the slide 242 is positioned at right angles to the table 13 and with its roller 272 against the shaped edge of the cam 284. Now the work is rotated and the work head 240 is being reciprocated and the grinding wheel is being rotated. The operator by turning wheel 31 feeds the table along to carry the work toward or in the direction of the tool head.

As the work is fed along it is moved laterally with the tool head in accordance with the configuration of the roller engaged face of the cam 284 and so the work is ground to the proper contour. By manipulating wheel 158 the tool head is fed laterally or transversely of the machine to keep the tool properly positioned to engage the work as the latter is carried toward the tool or in the direction of the tool head. With the various swivel adjustments disclosed the work and tool heads may be disposed in a wide range of relationships. The tool head may be adjusted by manipulation of the wheel 158 and also by adjustment of the horn 154 forwardly and rearwardly and by turning of the wheel 264 when the locking lug 271 is released.

The nut 274 is disposed to be engaged by the end of slide part 71 in the outermost position of the latter. Then at the end of a forward stroke of the table 13, the work and the work head, the handle or lever 95 is grasped by the operator and the slide part 71 held in a position with its said end against the nut 274 whereby during the return stroke of the parts the work is not engaged by the grinding wheel. That is during this return stroke the slide part 71 is held outwardly against the tendency of the coil springs 86 so that the side of the work which was in contact with the grinding wheel during the forward or working stroke is not engaged by the wheel during the return stroke and thus any back lash or play in the parts is always in the same direction.

Further nut 274 is located to prevent any excessive movement of the slide part 71 by the lever 95 or to prevent such lever being casually or accidentally used to move the slide part to such an extent as to bring some part or portion of the work into contact with the grinding wheel. The work of the machine of the modification is of the same high standard described in connection with the form of the machine first disclosed. The slight reciprocating movement of the work as the roller 272 is carried along the face of the cam 284 does not interfere with the functioning of the latter and such motion does improve the rate of cut, the finish of the completed work and the amount of material removed with a given wheel. It is to be understood that during the grinding operation the roller 272 is held against the cam 284 by the coil springs 86.

Referring now to the modification of Figs. 15, 16 and 17 the machine there shown is adapted for mounting on any suitable pedestal, table, bench or the like. The machine includes a base or mounting plate 290 having through its upper surface a longitudinally extending V-T slot 291 and toward one end a transverse V-T slot 292. One

of the base members 50 previously described is mounted on plate 290 and has its T-bolts entering the slot 291 whereby the base member may be adjusted along the plate.

Swivelly mounted on base member 50 in the manner described above in connection with Figs. 1 through 8, is a slide 293 and similarly mounted on slide 293 is a slide 294. Slides 293 and 294 are of identical construction and are of the construction of the slide 49 above described. Mounted for swivel adjustment on the slide 294 is a work head generally designated 295 and of the construction of the work head 47.

The hand levers for operating the slides 293 and 294 are designated 297 and 298 respectively and the radially disposed bolts for locking the swivel connection between slide 293 and base 50 are designated 299. The radial locking bolts for the swivel connection between the slide 294 and slide 293 are numbered 300 while the corresponding bolts for the swivel connection between the body 296 and the slide 294 are numbered 301. Otherwise where the parts of the work head and its supporting slides are the same as previously described they have the original reference characters applied to them to avoid unnecessary description.

T-bolts 302 having their heads in the slot 292 serve to secure a support 303 against the upper side of the end portion of the plate 290 for adjustment in directions transversely of such plate. In its upper side the support 303 is provided with a relatively wide slot or groove the edges of which are undercut providing dove-tail ways 304 receiving the dove-tail portion 305 of a slide 306. An adjustable gib 307 may be provided to take up for wear in the described ways.

A hand wheel 308 is secured to a shaft or screw 309 entering the slide and threaded through a portion or nut 310 rigid with the support 303. Thus on turning of the hand wheel 308 the same and the slide 306 will be moved transversely of the plate 290, either forwardly or rearwardly depending on the direction in which the wheel is turned. A collar 311 is disposed about the hub portion of the wheel 308 and a set screw 312 passes through said collar for securing it in various adjusted positions as will be understood from the previous description of similar parts.

Secured on the upper side of the slide 306 is a means 313 including a body 314 having lower flanges 315 through which securing screws 316 pass into the slide. A flange 317 integral with the body 314 has arcuate slots receiving stop bolts 318 adjustable in said slots. In its upper side the body 314 is provided with a tapered socket 319 receiving the lower portion of the tapered pilot or projection 171 of a slide 320 which is of the construction of the slide 172 of the form first described.

Extending from the swivel slide of the slide 320 is a bolt 321 passing through the projection or pilot thereof and having its lower end entering a recess or cored-out place 322 in the body 314. There a nut 323 is threaded to the bolt and has a long handle 324 by means of which it may be turned to draw the bolt downwardly and thus wedge the pilot in the socket 319. On release of the nut the slide 320 may be turned on the means 313 the pilot of the slide forming a center or pivot. On the upper side of the movable part of slide 320 is a tool head 325 and as said slide and the tool head and the means for reciprocating the slide are the same as in Figs. 1 through

8 and have been previously described in detail they are given the same reference characters in Figs. 15, 16 and 17 as originally and are not otherwise described.

Depending from the underside of the slide 320 are a pair of lugs 326 through each of which is threaded a screw 327 in horizontal alignment with the stop bolts 318. With this arrangement the bolts 318 are adjusted to the desired locations and then tightened in place. The bolts may be found not to stop the turning movement at the exact points desired when the nut 323 is loosened and the slide turned for adjustment. Then the screw 327 which has been brought to a stop bolt is given any fine or minute adjustment necessary to have the slide stopped in the exact location desired. In other words the bolts 318 provide for a coarse adjustment and the screws 327 for practically a micrometer adjustment.

The machine of the present modification is adapted for straight and multi-angle grinding but not for profile or contour grinding. Substantially everything that may be accomplished on the machine of Figs. 1 through 8 may be accomplished on the machine of Figs. 15, 16 and 17. In the modification the lower slide 293 takes the place of the table 13 of the first figures. While one of the slides 293 and 294 is being reciprocated the other of said slides is locked against casual movement by the tightening of its nut 107. Such slides may be secured at various angles to one another and the base plate 290 and the work head 295 is swivelly mounted on the slide 294 so that the work may be disposed with its center parallel with that of the grinding wheel 199 regardless of the angles at which the slides are disposed. With the adjustable support 303 and the slide 306 adjustable on the support the tool head 325 may be disposed at any point over a considerable range. Additionally the tool head is mounted on the slide 320 for swivel adjustment relative thereto and the slide is mounted for swivel adjustment on the means 313.

When grinding a hole of a diameter of .545 of an inch the work was revolved at various speeds from 275 R. P. M. to 500 R. P. M. The rate of reciprocation of the part reciprocated by power means (such part being the grinding wheel in the tests) was from 390 to 575 reciprocation per minute. During the mentioned tests the actual stroke of the reciprocating part was .0625 of an inch.

Having thus set forth the nature of my invention, what I claim is:

1. In a grinding machine, a base, a work head and a tool head on said base, means mounting the work head for adjustment on the base toward and from the tool head, means mounting the tool head for adjustment on the base in directions transverse to the directions in which the work head is adjustable, one of said heads including a reciprocable slide whereby said head may be reciprocated toward and from the other head, power operated means for imparting short, rapid reciprocating movements to said slide and thereby the head thereon, and other means for moving one of said heads toward and from the other in relative feeding movement of the work and tool.

2. In a grinding machine, a base, a work head and a tool head, one of said heads comprising a holder and means to rotate said holder, a reciprocable slide mounting the other of said heads,

swivel means mounting said slide for radial adjustment, means mounting the other of said heads on the upper side of said slide for reciprocation therewith, said other head including a holder, means on and movable with said slide and connected to rotate such holder, a bracket radially adjustable with said slide, power means on said bracket, and means operated by said power means and connected to reciprocate said slide.

3. In a grinding machine, a base, a tool head on said base toward one end thereof, a work head on said base and including means for supporting and rotating work for engagement by a tool of said tool head, said tool head comprising a support, a slide reciprocable on said support, means mounting said support on the base for radial adjustment, a spindle holder, means mounting said spindle holder on the last named slide for radial adjustment, a tool spindle in said holder, a motor on said holder, means to rotate said tool spindle from said motor, a bracket-like extension on said support, a motor on said extension, a crank means on said extension, means for driving said crank means from said motor, and means connecting the crank means with the last mentioned slide for reciprocation of the latter by said motor.

4. In a grinding machine, a base, a tool head on said base toward one end thereof, a table on said base and movable toward and from said tool head, a reciprocable slide, means mounting said slide on said table for adjustment longitudinally thereof and for adjustment radially with respect thereto, a spindle mount, means mounting said spindle mount on said slide for radial adjustment relative thereto, a work holder, a spindle in said mount and operable to rotate said work holder, a motor on said mount, means to drive said spindle from said motor, said tool head comprising a support, a slide reciprocable on said support, means mounting said support on the base for radial adjustment, a spindle holder, means mounting said spindle holder on the last named slide for radial adjustment, a tool spindle in said holder, a motor on said holder, means to rotate said tool spindle from said motor, a bracket-like extension on said support, a motor on said extension, crank means on said extension, means for driving said crank means from said motor, and means connecting said crank means with the last mentioned slide for reciprocation of the latter by the motor.

5. In a grinding machine, a table, means mounting said table for movement in the direction of its length, means to feed said table back and forth on said mounting means, a base member on said table and adjustable longitudinally thereof, a reciprocable slide, said base member having a socket opening through its upper side, a pilot depending from said slide and received in said socket whereby the slide is mounted for radial adjustment on said base member, means manually adjustable to act on said pilot and secure it and the slide in radially adjusted position, a work head including a work holder and means to rotate the latter, said slide having a socket opening through its upper side, a pilot on said work head and received in said socket in the slide whereby the work head is mounted on the slide for radial adjustment relative thereto, manually adjustable means to secure said pilot of the work head and thus the latter in a chosen position of radial adjustment on the slide, a tool head toward and from which the work head may be moved by feeding of the table and reciproca-

tion of the slide, said tool head including a tool holder and means to rotate the latter, a reciprocable slide on which the tool head is mounted, and a power means for rapidly reciprocating said slide.

6. In a grinding machine, a work head including a work holder and means for rotating the latter, a tool head including a tool holder and means to rotate the latter, means mounting said work holder, said means movable to carry the work holder toward and from the tool holder, and means mounting said tool head, said last means including a carriage, ways mounting said carriage for movements generally transversely to the paths of movement of the work holder, means for feeding said carriage on said ways, a horn-like support on the upper side of said carriage and adjustable thereon in parallel relation with said ways, a mounting device on the upper side of said support and rigid therewith, said device including a radial flange, stop bolts adjustable about said flange, said device having a socket opening through its upper side, a slide on said device and including a pilot received in said socket whereby the slide is radially adjustable on the device, means to secure the slide in the desired position of radial adjustment on the device, means on the slide to engage said stop bolts in preset positions of the latter to limit radial adjustment of the slide, said slide including a reciprocable part, mechanical means for reciprocating said part, and means mounting said tool head on the reciprocable part of said slide for movement therewith and for adjustment radially with respect thereto.

7. The combination as in claim 4 including means adjustable to vary the throw of said crank means and thus the length of the stroke of the slide.

8. In a grinding machine, a base, a tool head on said base toward one end thereof and including means for mounting and rotating a tool, a table on said base, means to adjust said table toward and from said tool head, a work head, a support, means mounting said support on the table for adjustment longitudinally thereof and for radial adjustment relative thereto, a slide reciprocable on said support, a bracket forming an extension of said slide, a motor on said bracket, crank means on said bracket, means for driving said crank means from said motor, means connecting said crank means with said slide for reciprocation of the latter by said motor, a second slide, means mounting the second slide on the first mentioned slide for swivel adjustment relative thereto, said work head including a spindle mount, means mounting said work head on the second mentioned slide for radial adjustment relative thereto, a work holder, a spindle in said mount and operable to rotate said work holder, and means including a motor on said mount for rotating said spindle.

9. In a grinding machine, a base, a tool head on said base toward one end thereof, a support, means mounting said support on said base for adjustment transversely thereof, a slide on said support, threaded means for feeding said slide on said support, said tool head including a spindle holder, means mounting said tool head on the slide for radial adjustment relative thereto, a motor on said spindle holder, means whereby said motor may drive a tool spindle supported by said holder, a table on said base, means to adjust said table toward and from said tool head, a work head on said table, said work head including a base member, means mounting said

base member on the table for adjustment longitudinally thereof, a reciprocable slide on the base member, a bracket forming an extension of a part of said slide, a motor on said bracket, crank means on said bracket, means for driving said crank means from said motor, means connecting said crank means with another part of said slide for reciprocation thereof by the motor, a second slide, means mounting the second slide on the movable part of the first mentioned slide for swivel adjustment relative thereto, a spindle mount, means mounting said spindle mount on the second mentioned slide for radial adjustment relative thereto, a work holder, a spindle in said mount and operable to rotate said work holder, and means including a motor on said mount for rotating said spindle.

10. In a grinding machine, a support, a tool head toward one end of said support, a table on said support and movable toward and from said tool head, means for mounting a cam at one side of the path of movement of said table, a base member on and adjustable longitudinally of said table, a slide including a relatively stationary part mounted on said base member for radial adjustment relative thereto and a movable part reciprocable on said relatively stationary part, power means for reciprocating the movable part of said slide, a second slide mounted on the movable part of said slide and including a relatively stationary part swivelly mounted and a movable part reciprocable on said stationary part, a work head on the movable part of the second slide and including a work holder and means to rotate the same, said second slide cross-wise of the first slide for reciprocation of the movable part of the second slide at right angles to the direction of reciprocation of the first mentioned slide, a roller on the movable part of the second slide for engagement with a cam on the cam mounting means, and spring means biasing the movable part of the second slide in a direction to maintain said roller in engagement with a cam on said cam mounting means.

11. The combination as in claim 10 including a hand lever for manual control of movements of said movable part of the second slide in opposition to said spring means.

12. In a grinding machine, a tool head including means for holding and rotating a tool, a work head including means for holding and rotating a piece of work, means for feeding the work head toward said tool head to engage a piece of work with a tool, power operated means on said means for imparting short, rapid, reciprocating movements to the work head as the work is engaged by the tool, and cam controlled means mounting the work head for movements transverse to the directions of feed of such head toward and from the tool head.

13. In a grinding machine, a base having a V-T slot therein toward one end thereof and a V-T slot therein extending at right angles to the first V-T slot, a base member on said base and adjustable thereon along the second mentioned slot, a slide including a relatively stationary part mounted on said base member for radial adjustment relative thereto and a movable part reciprocable on said stationary part, a second slide including a relatively stationary part mounted on the movable part of the first mentioned slide for radial adjustment relative thereto and a movable part reciprocable on the relatively stationary part, a work head mounted on the movable part of the second slide for radial

adjustment relative thereto and including a work holder and means for rotating the same, a manually manipulatable means on each of said slides for locking the movable part thereof to the relatively stationary part thereof, a hand lever on each of said slides for manual movement of the movable parts thereof, a support adjustable on the base along the first mentioned V-T slot and having ways in its upper side in alignment with said slot, a slide on said ways and means to move said slide therealong, means on the upper side of said slide and having a socket therein, a slide on said means and including a relatively stationary part having a pilot in said socket for radial adjustment of the slide and a movable part reciprocable on the relatively stationary part, a tool head on the movable part of the last mentioned slide for movement therewith and for radial adjustment relative thereto, said tool head including a tool holder and means to rotate the latter, and power means for imparting a rapid short-stroke reciprocating movement to the movable part of the last mentioned slide.

14. The combination as in claim 13 wherein said power means is mounted by the relatively stationary part of the last mentioned slide and is independent of all other parts of the machine.

15. In a grinding machine, a work head, a pair of slides under and supporting said work head and independently adjustable radially with respect to the head and one another, manual means for selectively operating said slides, a tool head, a pair of slides under said tool head and generally at right angles to one another, means mounting the lower of said pair of slides for adjustment transversely to the direction in which the work head is located with respect to the tool head, the upper of the slides of the second mentioned pair including a relatively stationary part and a movable part reciprocable thereon, means mounting the relatively stationary part of the upper of said slides for radial adjustment, means mounting the tool head on the movable part of the upper of the slides of the second mentioned pair for radial adjustment relative thereto, and power operated means for imparting short-stroke reciprocating movements to the movable part of the upper of the slides of the second mentioned pair.

16. In a grinding machine, a work head and a tool head, means mounting the first of said heads for movement toward and from the second thereof in each of at least two predetermined angularly related planes, means for reciprocating the second of said heads, and means adjustably mounting said second head to dispose it for reciprocation in parallel relation with each predetermined plane of movement of the first head.

17. In a grinding machine, a table, a pair of heads comprising a first and a second head, a first slide, swivel means mounting said slide on said table for radial adjustment relative thereto, swivel means mounting the first of said heads on said slide for radial adjustment relative thereto, a second slide, swivel means mounting said second slide for radial adjustment, swivel means mounting said second head on said second slide for radial adjustment relative thereto, power means for reciprocating said second slide, means mounting said table for movement to carry the first slide and head toward and from the second head, manual means for moving said first slide to carry the first head toward the second head, and said swivel mounting of the second slide and second head providing for adjustment of such parts

whereby the second head will be reciprocated by the second slide in a plane parallel with the plane of movement of the first head by said table and the first slide in various positions of adjustment of the latter.

18. The machine as in claim 17 including a carriage on which said second slide is mounted and means for adjusting said carriage in a path transverse to the path of movement of said table.

19. In a grinding machine, a work holder, a tool holder, independent means for rotating the respective holders, a slide mounting one of said holders for reciprocating movement relative to the other thereof, power operated means for reciprocating said slide and thus said holder, said slide including a base portion and a movable portion, said portions engaging over horizontal surface portions and inclined surface portions, and said inclined engaging surface portions of greater area than said horizontal surface portions.

20. A slide for use in a machine, said slide including a base portion having inclined edge portions diverging from the upper surface thereof and upper bearing surfaces between said edge portions, a movable slide portion on said base portion and including bearing surfaces engaging the upper bearing surfaces and the inclined edge portions of said base portion, and said outwardly inclining edge portions of the base and the portions of the movable slide portion engaging the same of greater area than the upper bearing surfaces of said base portion and the bearing surfaces of said movable slide portion engaging the same.

21. In a grinding machine, a bed, a table, means to move said table on said bed, a carriage, means to move said carriage in directions at right angles to the directions in which said table may be moved, a slide mounted on said table for swivel adjustment relative thereto, a slide mounted on said carriage for swivel adjustment relative thereto, a work head and a tool head each mounted on one of said slides, and power means for reciprocating one of said slides.

22. In a grinding machine, a bed, a table, means to move said table on said bed, a carriage, means to move said carriage in directions at right angles to the directions in which said table may be moved, a slide mounted on said table for swivel adjustment relative thereto, a slide mounted on said carriage for swivel adjustment relative thereto, a work head and a tool head each mounted on one of said slides for swivel adjustment relative thereto, and power means for reciprocating one of said slides.

23. In a grinding machine, a bed, a table, means to move said table on said bed, a carriage, means to move said carriage in directions at right angles to the directions in which said table may be moved, a slide mounted on said table for swivel adjustment relative thereto, a slide mounted on said carriage for swivel adjustment relative thereto, a work head and a tool head each mounted on one of said slides, each of said heads comprising a holder and a motor for rotating said holder, and power means for reciprocating one of said slides.

24. In a grinding machine, a bed, a table, means to move said table on said bed, a carriage, means to move said carriage in directions at

right angles to directions in which said table may be moved, a slide mounted on said table for swivel adjustment relative thereto, a slide mounted on said carriage for swivel adjustment relative thereto, a work head and a tool head each mounted on one of said slides for swivel adjustment relative thereto, each of said heads comprising a holder and a motor for rotating said holder, and power means for reciprocating one of said slides.

25. In a grinding machine, a bed, a table, means to move said table on said bed, a carriage, means to move said carriage in directions at right angles to the directions in which said table may be moved, a slide mounted on said table for swivel adjustment relative thereto, means to lock said slide against all movement relative to said table, a slide mounted on said carriage for swivel adjustment relative thereto, a work head and a tool head each mounted on one of said slides, and power means for reciprocating one of said slides.

26. In a grinding machine, a first head, a pair of slides under and supporting said first head and independently adjustable radially with respect to the head and one another, manual means for selectively operating said slides, a second head, a pair of slides under said second head and generally at right angles to one another, means mounting the lower of said pair of slides for adjustment transversely to the direction in which the first head is located with respect to the second head, the upper of the slides of the second mentioned pair including a relatively stationary part and a movable part reciprocable thereon, means mounting the relatively stationary part of the upper of said slides for radial adjustment, means mounting the second head on the movable part of the upper of the slides of the second mentioned pair for radial adjustment relative thereto, and power operated means for imparting short stroke reciprocating movements to the movable part of the upper of the slides of the second mentioned pair.

27. In a grinding machine, a work head and a tool head each comprising a holder and a motor for rotating the holder, a pair of slides disposed one on the other, means mounting said slides for relative radial adjustment in horizontal planes, means mounting one of said heads on the upper of said slides and movable therewith, power operating means for imparting short, rapid reciprocating movements to said slide and thereby said head, and other means for moving one of said heads toward and from the other for relative feeding of a piece of work and a tool.

28. In a grinding machine, a work head and a tool head each comprising a holder and a motor for rotating the holder, a pair of slides disposed one on the other, means mounting said slides for relative radial adjustment in horizontal planes, means swivelly mounting one of said heads on the upper of said slides and movable therewith, power operated means for imparting short, rapid reciprocating movements to said slide and thereby said head, and other means for moving one of said heads toward and from the other for relative feeding of a piece of work and a tool.

WALTER G. WEISSMAN.
